[57] **CLAIM**

The ornamental design for a compact disc holder, as shown and described.

DESCRIPTION

FIG. 1 is a top, front and side perspective view of a 10-disc compact disc holder showing our new design;

FIG. 2 is a front elevational view thereof;

FIG. 3 is a side elevational view thereof;

FIG. 4 is a top plan view thereof;

FIG. 5 is a bottom plan view thereof;

FIG. 6 is a top, front, and side perspective view of a second embodiment of a compact disc holder, showing a 15-disc compact disc holder;

FIG. 7 is a front elevational view thereof;

FIG. 8 is a side elevational view thereof;

FIG. 9 is a top plan view thereof;

FIG. 10 is a bottom plan view thereof;

FIG. 11 is a top, front, and side perspective view of a third embodiment of a compact disc holder, showing a 20-disc compact disc holder;

FIG. 12 is a front elevational view thereof;

FIG. 13 is a side elevational view thereof;

FIG. 14 is a top plan view thereof; and,

FIG. 15 is a bottom plan view thereof.
